(57) **CLAIM**

The ornamental design for a fire chief stationery clip, as shown and described.

DESCRIPTION

FIG. 1 is a front view of a fire chief stationery clip in accordance with my new design;

FIG. 2 is a rear view of the fire chief stationery clip shown in FIG. 1;

FIG. 3 is a perspective view of the fire chief stationery clip shown in FIG. 1;

FIG. 4 is a left side view of the fire chief stationery clip shown in FIG. 1;

FIG. 5 is a right side view of the fire chief stationery clip shown in FIG. 1;

FIG. 6 is a top view of the fire chief stationery clip shown in FIG. 1; and,

FIG. 7 is a bottom view of the fire chief stationery clip shown in FIG. 1.

The long and short broken lines around the inside edge of the fire chief stationery clip define the bounds of the claimed design and form no part thereof.

The evenly spaced broken lines showing the clip and apertures in the center of the fire chief stationery clip show portions that form no part of the claimed design.
